United States Patent Office

Des. 186,153
Patented Sept. 22, 1959

186,153

SWIVELING BATHTUB OR SIMILAR ARTICLE

Henry Dreyfuss, South Pasadena, Calif., assignor to Crane Co., Chicago, Ill., a corporation of Illinois

Application August 8, 1958, Serial No. 52,133

Term of patent 14 years

(Cl. D4—4)

Fig. 1 is a bottom view of a swiveling bathtub in the folded position embodying my design;

Fig. 2 is a sideview of the article in the unfolded position;

Fig. 3 is a side view in the folded position; and

Fig. 4 is a perspective view of the article in the unfolded position.

The dotted lines are for illustrative purposes only.

I claim:

The ornamental design for a swiveling bathtub or similar article, substantially as shown and described.
